(57) **CLAIM**

I claim the ornamental design for a fishing lure trolling spoon, substantially as shown.

DESCRIPTION

FIG. 1 is a top perspective view of the fishing lure trolling spoon showing my new design;

FIG. 2 is a top plan view thereof;

FIG. 3 is a bottom view thereof;

FIG. 4 is a right side view, the left side view being a mirror image thereof;

FIG. 5 is a rear view thereof;

FIG. 6 is a front view thereof;

FIG. 7 is a cross sectional view taken along line 7-7 of FIG. 2; and,

FIG. 8 is a cross sectional view taken along line 8-8 of FIG. 2.
